TENSION CONTROL FOR WIRE WEAVING MACHINES

Noah S. Harter, Waukegan, Ill., assignor to Cyclone Fence Company, Waukegan, Ill., a corporation of Illinois

Application June 20, 1934, Serial No. 731,552

3 Claims. (Cl. 139—353)

The invention relates to tension control means for looms and particularly wire weaving looms used in the manufacture of wire screen fabric.

In the type of loom with which the present invention is concerned the warp wires are unwound from a plurality of spools, caused to converge and directed over rollers for delivery to a receiving frame from which they are fed to the weaving machine. The frame constructed in accordance with the present invention receives wires from spool racks positioned opposite the frame and to the respective sides thereof and operates to collect and align the wires for passage through automatic tension control mechanism. Accordingly, the primary object of the invention is to provide means for collecting and feeding warp wires to a weaving machine and which will maintain the wires under a tension that will be substantially uniform for all the wires.

A further object is to provide automatic mechanism for stopping the operation of the weaving machine in the event a wire should break in which case the tension of the wire becomes zero and which will also operate to bring the machine to a stop should the tension on the wire exceed a set limit.

With these and various other objects in view, the invention may consist of certain novel features of construction and operation as will be more fully described and particularly pointed out in the specification, drawings and claims appended hereto.

In the drawings which illustrate an embodiment of the device and wherein like reference characters are used to designate like parts,

Figure 1 is a plan view of the warp wire receiving frame embodying the improvements of the present invention;

Figure 2 is a top plan view of the structure of Figure 1;

Figure 3 is an elevational view looking toward the right of Figure 1;

Figure 4 is a vertical sectional view taken substantially through the center of the frame;

Figure 5 is a detail sectional view showing the electric control wires and their manner of attachment to the frame, and

Figure 6 is a diagrammatic view showing the electrical connections for the tension control wires.

The frame selected for illustration in the accompanying drawings consists of spaced vertical uprights 10 and 11 of channel-shaped form having secured to their upper ends the integral frame 12 of substantially rectangular shape and

which is reinforced by members 13 extending parallel with the end members of the integral frame. The members 13 are suitably spaced from each other to provide journalling means for the roller 14 and project a distance to the rear of the receiving frame, that is, to the side opposite the weaving machine for securement to any suitable support, not shown. Secured adjacent the ends of the integral frame 12 are guide members 15 and 16, respectively, formed by angle brackets and which are provided with a plurality of spaced openings 17 for receiving the warp wires W. These openings maintain the wires in proper spaced relation for travel over the end rollers 18 and 19 suitably journaled in the integral frame 12 adjacent the respective guide members.

Other warp wires are directed over the main roller 14 which in conjunction with the end rollers converge the wires for passage through the upper main guide member 20. The member is also formed by an angle bracket which extends the full width of the frame from upright 10 to upright 11, being secured thereto by brackets 21. Openings 22 are provided in the base flange of the member in spaced relation for receiving and directing all of the wires passing through the frame. It will be observed by reference to Figure 2 that the end rollers 18 and 19 are disposed at right angles to that of the main roller 14 and that these end rollers receive wires which approach the receiving frame at right angles to those wires passing over the main roller 14. The structure, however, properly guides and directs the wires and the main upper guide member 20 aligns the wires so that they form a single set of uniformly spaced wires for presentation to the tension control mechanism which will be presently described.

The lower main guide member 23 extending the width of the frame and being supported by brackets 24 is also provided with a plurality of openings for receiving and properly spacing the wires prior to their travel over the roller 25, whereupon they leave the receiving frame and are delivered to a wire weaving machine of any suitable construction, not shown. It will be noted that guide member 23 is positioned outwardly of the uprights 10 and 11 to the rear of the receiving frame and is out of vertical alignment with the upper guide member 20 located substantially centrally of the spaced uprights. Roller 25 is journaled in pivoted arms 26 pivoted at 27 to brackets suitably secured to the uprights 10 and 11, respectively.

The tension indicating means consists essentially of a pair of spaced electric wires 28 and 30, Figure 5, connecting at their ends with coil springs 31 which in turn are suitably secured to supports 32 and 33, respectively, which are insulated from the uprights by rubber washers 34. The supports 32 for wire 28 are in the form of a crank arm which upon rotation of the arm provides for adjustment of the position of the wire 28 with respect to wire 30. Rods 35 and 36 are supported in spaced relation vertically of the uprights by brackets 37 and have suitably secured thereto the flanges 38. The flange on rod 35 is directed upwardly, whereas, the flange on rod 36 is directed downwardly, thus providing opposed supports for detachably securing the tension indicators. These comprise a metal strip 40 having a slot at one end for engagement with the upper flange on rod 35 and a coil spring 41 connecting with latch 42 for engagement with the lower flange secured to the rod 36. Suitably fastened as by welding to metal strip 40 at substantially the mid-point of its length is a hook 43 which is hooked around its respective wire to thereby hold the same out of contact with the electric wires 28 and 30. A tension indicator is provided for each warp wire passing through the frame and it will be understood that the coil spring 41 is selected with respect to the particular tension to be maintained in the wires W and that when said tension is established the metal strip 40 and coil springs 41 are substantially vertical. Due to the fact that the upper and lower guide members are out of vertical alignment, as described, the wires W tend to engage the electric contact wire 28 but are restrained from doing so by their engagement with hook 43 of the tension indicator.

In Figure 6 the motor M for operating the weaving machine is shown electrically connected to power lines L¹ and L², the latter having a switch 44 for interrupting the circuit to the motor. This switch is of the gravity closing type, or may be positively closed by resilient means, and is operated by an electro-magnet 45 which electrically connects with wires 46 and 47, the latter having in circuit therewith the battery 48. Conductor 49 leading from the electro-magnet connects with both wires 28 and 30, which as previously described are insulated from the frame while conductor 47 is grounded at 50 to the frame.

It will be observed from the foregoing that should the tension on any particular warp wire vary by reason of the spool sticking, which would increase the tension on the wire, or by reason of a wire breaking, the particular wire is brought into contact with either of the electric wires 28 or 30. This results in closing the electric circuit to the electro-magnet 45 which upon energization will lift switch 44 to interrupt the power circuit to the motor operating the weaving machine. The weaving machine therefore stops and the operator is thereby informed that the warp wires require attention. In the event that the tension on any one wire exceeds the limit determined by the coil spring 41 the hook 43 will be drawn outwardly, causing an elongation of spring 41 and a displacement of the particular indicator with respect to the remaining indicators. The operator will be able to spot the particular wire giving trouble and by tracing the same back to its source the cause for the increased tension can be determined. When the trouble is the result of a broken wire the slack

in said wire is readily visible to the operator. Ordinarily the warp wires will be in alignment and present a uniform appearance in their travel through the receiving frame. By reason of the frame and the tension indicating means of the invention it is relatively easy for the operator to locate trouble that develops with respect to the wires.

It is to be understood that I do not wish to be limited by the exact embodiment of the device shown, which is merely by way of illustration and not limitation, as various and other forms of the device will of course be apparent to those skilled in the art without departing from the spirit of the invention or the scope of the claims.

I claim:

1. In a device of the kind described, a frame for receiving a plurality of warp wires and for delivering said wires to a weaving machine for further operations, spaced means supported by said frame engaging the warp wires and aligning the same transversely of said frame, a tension indicator associated with each warp wire at a point between the spaced means, each tension indicator yieldingly holding the wire out of its normal direction, and said tension indicators holding said wires in alignment transversely of the frame when the tension on the warp wires is substantially uniform, and contact means supported by the frame and normally spaced from the warp wires, said warp wires being adapted to engage the contact means when the tension on the warp wires exceeds a predetermined limit.

2. In a device of the kind described, a frame for receiving a plurality of warp wires and for delivering said wires to a wire weaving machine, said frame extending vertically and receiving the warp wires at the top and delivering them at the base, a tension indicator associated with each warp wire and carried by the frame, each of said indicators yieldingly holding its respective wire out of its normal direction when the same is under normal tension, whereby visible indication is given as to the particular wire when the tension on the same exceeds a predetermined limit, and a contact wire also supported by the frame and normally spaced from the warp wires, said warp wires being adapted to engage the contact wire when the tension on the warp wires exceeds the predetermined limit.

3. In a device of the kind described, a frame for receiving a plurality of warp wires and for delivering said wires to a wire weaving machine, said frame extending vertically and receiving the warp wires at the top and delivering them at the base, a tension indicator associated with each warp wire and carried by the frame, each indicator comprising a member detachable with respect to its warp wire, and resilient means attaching the same to the frame, each of said indicators yieldingly holding its respective warp wire out of its normal direction when the same is under normal tension, whereby visible indication is given as to the particular wire when the tension on the same exceeds a predetermined limit, and spaced contact wires supported by and extending transversely of the frame and normally spaced from the warp wires, said warp wires being adapted to engage one or the other of said contact wires when the tension on the warp wires exceeds the predetermined limit or drops below a predetermined minimum.

NOAH S. HARTER.
